GUARD FOR PRIMER VALVES

Harry W. Klosterman, Portland, Oreg.

Application May 17, 1937, Serial No. 143,046

1 Claim. (Cl. 182—12)

This invention relates generally to the plumbing industry, and particularly to a guard for primer valves.

The main object of this invention is the provision of a simple and efficient guard for preventing the formation of a closed connection between a primer valve and a floor drain trap.

The second object is to provide an improved form of connection between the valve and the trap which would prevent the splashing of water from the seal breaking opening.

I accomplish these and other objects in the manner set forth in the following specification as illustrated in the accompanying drawing, in

15 which:

Fig. 1 is a longitudinal section through the valve equipped with my guard showing a closed position with no water flowing through the valve.

Fig. 2 is a view similar to Fig. 1 showing the 20 position of the valve parts when a faucet is being opened.

Fig. 3 is a view similar to Fig. 2 but showing the position of the parts when the faucet is wide open.

25 Fig. 4 is a section taken along the line 4—4 in Fig. 3.

Fig. 5 is a fragmentary section of a modified form of the device taken along the line 5—5 in Fig. 6.

30 Fig. 6 is a transverse section taken along the line 6—6 in Fig. 5.

Fig. 7 is a perspective view of the modified form of guard shown in Figs. 5 and 6.

Fig. 8 is an assembled view showing the 35 relation of the primer valve to the faucet and trap.

Similar numerals refer to similar parts throughout the several views.

Before entering into an explanation of this invention, attention is drawn to the patent of Bale

40 No. 1,981,540, to which the present invention applies. It will be understood that the purpose of a primer valve is to insure the maintenance of a

water seal in a floor drain trap. Plumbing codes require that the connection between the primer

45 valve and the trap be open in order to prevent any possibility of contamination of the fresh water supply line. In order to insure this, one or

more openings are made in the connection between the primer valve and the floor drain trap.

50 Experience, however, has indicated that such openings may easily become clogged or material may pass through these openings and fall into the fitting itself. In order to avoid these con-

55 ditions, I have provided a special guard which

will prevent obstructions from being placed in the opening or falling into same.

Referring in detail to the drawing, there is shown a body 10 of a primer valve whose inlet opening 11 is connected to a fresh water supply 5 pipe 12 and whose outlet opening 13 is connected to a faucet 14 by means of a pipe 15. The openings 11 and 13 communicate with the cylindrical chamber 16 by way of the ports 17 and 18 which are offset with relation to each other. 10

Within the chamber 16 is a piston 19 to which is attached an elongated stem 20 on whose lower end is secured a washer 21. The stem 20 is free to pass through an opening 22 in the wall 23 of the body 10. Formed in the body 10 is a metering chamber 24 into which the stem 20 projects. At the lower end of the metering chamber 24 and screwed into the wall 25 is a nipple 26 which is provided with an axial opening 27 and lateral openings 28. The body 10 is provided with lateral openings 29 which are disposed between the wall 25 and the lower end 30 of the nipple 26. 15 20

The lower end 31 of the body 10 is preferably threaded to receive the union 32. The end 31 is connected by the union 32 to the pipe 33 which 25 communicates with the floor drain trap 34. It is desirable to provide an opening 35 in the body 10 for drainage purposes. A groove 36 is also formed in the piston 19.

The operation of the valve is identical with the 30 operation of the valve described in the Bale Patent No. 1,981,540. Briefly, it is as follows:

When the faucet 14 is opened, the water entering the chamber 16 through the port 17 causes the piston 19 to rise, as shown in Fig. 2, raising 35 the washer 21 from the seat 37 which is formed on the upper end of the nipple 26. A further upward movement of the piston 19, as shown in Fig. 3, permits the water to pass through the port 18 to the faucet 14. The water which occupied the 40 metering chamber 24 is thereby allowed to escape through the opening 27 into the trap 34. It will be noted that the axis of the openings 28 is normal to the axis of the opening 29. In other words, while this does not afford visibility, it does 45 insure a break in the connection. For construction purposes a threaded cap 38 is employed at the upper end of the chamber 16.

In the form of the device shown in Figs. 5 to 7, inclusive, instead of using the equivalent of the 50 nipple 26, I merely employ a band clamp 39 which encircles the reduced portion 40 of the body 41 and is held permanently in position by the pin 42 which is driven through the holes 42A into the hole 42B in the wall 43 of the body 41. 55

The clamp 39 is provided with the holes 44 which are disposed between the openings 45 in the portion 43.

This form of guard is identical in its functioning with the form shown in Figs. 1 to 4, inclusive, it being the object in both cases to provide a guard which will prevent playful or accidental interference with the operation of the primer valve.

10 I claim:

A primer valve of the class described having a

metering chamber formed within same, a nipple extending downwardly from said metering chamber, a valve for controlling the flow of liquid through said nipple, a wall surrounding said nipple and spaced therefrom, said wall forming a means for connecting the discharge from said nipple to a sanitary system, said wall and nipple having lateral openings therein out of alignment with each other.

HARRY W. KLOSTERMAN. 10
